UNITED STATES PATENT OFFICE.

MILTON W. WINTERMUTE, OF BUFFALO, NEW YORK.

JOINT-FASTENER.

942,693.

Specification of Letters Patent.

Patented Dec. 7, 1909.

Application filed June 9, 1909. Serial No. 501,065.

To all whom it may concern:

Be it known that I, MILTON W. WINTERMUTE, a citizen of the United States, residing at Buffalo, in the county of Erie and State of New York, have invented certain new and useful Improvements in Joint-Fasteners; and I do hereby declare the following to be a full, clear, and exact description of the invention, such as will enable others skilled in the art to which it appertains to make and use the same.

This invention relates to joint fastenings and has for an object to provide means for securing together wooden or like joints by driving and without the employment of wedges, glue or other cementing material.

A further object of the invention is to provide a device constructed of resilient sheet material having stamped-up portions formed therein adapted to permit the driving of sections of the joint together but offering resistance to return movement of such driven parts.

With these and other objects in view, the invention comprises certain novel constructions, combinations and arrangements of parts, as will be hereinafter fully described and claimed:

In the drawings:—Figure 1 is a view of the invention associated with a conventional furniture joint, it being understood, however, that the use of the invention is not limited to furniture joints. Fig. 2 is a perspective view of the cylindrical fastening member such as is shown in association with the chair parts of Fig. 1 and for securing a round spindle or tenon. Fig. 3 is an embodiment of the invention adapted to secure a flat or rectangular tenon. Fig. 4 is a longitudinal sectional view taken through the device as shown in Fig. 3. Fig. 5 is a transverse sectional view taken through the embodiment shown at Fig. 3.

Like characters of reference designate corresponding parts throughout the several views.

It is well known that wood and like joints employing tenon connections or the equivalents are ordinarily secured by the employment of wedges or glue, the latter being a satisfactory means for connecting such joints until the parts become dry or until the glue is broken by sharp rapping and the like. When either of these contingencies occur the glue ordinarily employed breaks away permitting the parts to separate. The

present invention embodies improved means for securing such parts together without the employment of glue and comprises as shown at Figs. 1 and 2 a cylinder 10 composed of 60 resilient sheet metal having short slits cut therein and the material upon each side of the slit stamped in opposite directions as shown plainly at 11 and 12, the former being supposed to be stamped inwardly and 65 the latter outwardly. Preferably these stamped-up portions are triangular or pyramidal in formation presenting more or less sharp points 13 both within and without the cylinder. The cylindrical fastener 70 shown at Figs. 2 and 3 are, of course, adapted for securing together round tenon joints as the ends 14 of legs 15 or rounds 16. To enable the rounds to be more conveniently driven one end of the cylinder is preferably 75 made slightly larger than the other as indicated by the slit 17, so that before the fastener is put into operation it is not in fact a true cylinder but is very slightly enlarged at one end to permit the introduction of the 80 round 14. When the end of the round is introduced into the end of the cylinder the opposite end of the cylinder is introduced 85 into the hole and the parts then driven together. It will also be apparent that the 85 cylinder may first be introduced into the hole, and the tenon slightly tapered or rounded at the end may be driven into the fastener so positioned. In the driving, the stamped-up portions 11 and 12 are forced or 90 compressed toward the plane of the cylinder it being understood that the round to be driven is of a diameter approximately equal to the diameter of the hole less the thickness 95 of the material of the fastener.

It will be apparent that when the driving has ceased the stamped-up portions 11 and 12 will spring to some extent outwardly and the points 13 embed themselves into the wood adjacent. The reverse position of the 100 inclinations of the stamped-up portions 11 and 12 will prevent the withdrawal of the parts and the forming of the tenon of a diameter substantially equal to the diameter 105 of the hole less the thickness of the material will prevent lateral movement thereof.

At Figs. 3, 4, and 5, the fastener is shown constructed substantially U-shaped as seen at 10', the stamped-up portions 11 and 12 being similar in all respects to the stamped-up portions shown at Fig. 2 and provided with similar points 13. The latter form is

intended to be used for a flat or rectangular tenon and in operation is employed exactly as the device shown at Figs. 1 and 2 is employed.

5 What I claim is:—

1. A joint fastener, composed of resilient sheet material having slits formed therein with the material upon opposite sides of the slits stamped in opposite directions and with 10 oppositely directed inclinations.

2. A joint fastener comprising sheet material and with engaging members disposed upon opposite sides of the sheet having adjacent engaging faces and oppositely disposed 15 inclinations.

3. A joint fastener composed of resilient sheet material with semipyramidal engaging portions stamped up from the sheet, the semipyramids upon opposite sides of the sheet 20 having their apexes oppositely disposed.

4. A joint fastener composed of resilient sheet material with semipyramidal engaging portions stamped up from the sheet, with the bases of semipyramids upon the opposite 25 sides of the sheet adjacent and their apexes oppositely disposed.

5. A joint fastener composed of resilient

sheet material with similarly formed semi-pyramidal engaging portions stamped up from opposite sides of the sheet.

6. A joint fastening composed of resilient sheet material with similarly formed oppositely directed semipyramidal engaging portions stamped up from the opposite sides of the sheet.

7. A joint fastener composed of resilient sheet material with similarly formed semi-pyramidal engaging portions stamped up from opposite sides of the sheet, with the apexes of the semipyramids upon opposite 40 sides of the sheet oppositely directed.

8. A joint fastener composed of resilient sheet material with similarly formed semi-pyramidal engaging portions stamped up from opposite sides of the sheet, with the 45 bases of the semipyramids upon opposite sides of the sheet adjacent and their apexes oppositely disposed.

In testimony whereof I affix my signature in presence of two witnesses.

MILTON W. WINTERMUTE.
